US00D386866S

United States Patent

[19]

Craft et al.

[11] Patent Number: Des. 386,866[45] Date of Patent: *Nov. 25, 1997[54] REFUSE CONTAINER BASE

[75] Inventors: Charles W. Craft, Apple Creek; Stephen P. Casteel, Wadsworth, both of Ohio; Richard O'Grady, Southington, Conn.

[73] Assignee: Rubbermaid Incorporated, Wooster, Ohio

[] Term: 14 Years

[21] Appl. No.: 53,213

[22] Filed: Apr. 17, 1996

[51] LOC (6) Cl. 09-09

[52] U.S. Cl. D34/1

[58] Field of Search .... D34/1, 5-7, 10; D32/37; 232/43.2, 1 R; 220/908-911, 404

Primary Examiner—Louis S. Zarfas*Assistant Examiner*—Robin V. Taylor*Attorney, Agent, or Firm*—Richard B. O'Planick; Lisa B. Riedesel[57] CLAIM

The ornamental design for a refuse container base, as shown and described.

DESCRIPTION

FIG. 1 is a top left front perspective view of a refuse container base, showing our new design;

FIG. 2 is a right side elevational view thereof; the left side elevational view being a mirror image;

FIG. 3 is a front elevational view thereof;

FIG. 4 is a rear elevational view thereof; and,

FIG. 5 is a top plan view thereof.
